[57] CLAIM

The ornamental design for a hair styling apparatus, as shown and described.

DESCRIPTION

FIG. 1 is a top perspective view showing my new design; FIG. 2 is a top plan view thereon;

FIG. 3 is a side view seen from the left of FIG. 1;

FIG. 4 is a bottom perspective view seen from the opposite side of FIG. 1; and,

FIG. 5 is a bottom perspective showing my design in an alternate position.

The portions of the hair styling apparatus that are not shown in the drawings are not being claimed.

Broken lines which define the bounds of the claim in FIGS. 4 and 5 form no part thereof.
